GARMENT

Alex E. Swanson, Chicago, Ill., assignor to E. R. Moore Company, a corporation of Illinois

Application April 6, 1933, Serial No. 664,679

2 Claims. (Cl. 2—78)

My invention relates to improvements in the construction of garments, and more particularly to a class of garments suitable for wear in participating in athletic events and which are familiarly known as gym suits.

My invention relates more particularly to garments of this type adapted to be worn by girls or young women of grade school, high school or college age, and has for a purpose the provision of an improved garment having many advantages and features not found in the present garments.

A popular type of gym suit on the market today is a one-piece suit consisting of a bloomer portion and a bodice portion fastened together at the waist line, the bodice portion having buttons at the shoulder on one side and button holes on the other side so that robing or disrobing can be effected only by manipulation of the buttons. This action consumes a definite period of time and also causes an unattractive appearance of the suit on the person for the reason that the buttons on the shoulder are distinctly unsightly. Further, a belt either separate or attached to the bodice is generally demanded by the average wearer of the suit and the belt must be buttoned or unbuttoned in robing or disrobing.

A further objection to the suits of this type lies in the problem of laundering. Buttons are frequently snapped off or broken during laundering. The removable belts are lost or misplaced, and thus handling of a large number of these suits involves considerable trouble and expense.

The object of the present invention is to provide a gym suit so constructed that all of the above mentioned defects of the suits at present sold on the market are eliminated.

A further object of my invention is to provide a gym suit of the type described so constructed that attiring in the same or disrobing therefrom are both much more easily and quickly accomplished.

A further object is to provide an improved garment of the type described which is so constructed that the greatest degree of comfort is attained by the wearer both in a normal and in an exercising position.

A further object of the present invention is to provide a garment of the type described that can be securely fastened on the wearer without buttons or belts, thereby eliminating losses caused in laundering the same, or in any other manner.

A further object is to provide an improved garment of the class described capable of automatic adjustment to fit the individual size of the

wearer within certain wide limits, thereby eliminating the necessity of manufacturing a greater number of sizes to meet a group requirement.

Other objects and advantages will be readily apparent from the following description wherein reference is had to the accompanying two sheets of drawings upon which

Fig. 1 is a front illustration of the garment showing appearance of the same when worn by an average sized girl;

Fig. 2 is a similar view looking from the back;

Fig. 3 is a front view of the garment showing the bodice portion opened; and

Fig. 4 is a fragmentary view from the left side showing the opening for the strap of the fixed front bodice portion.

In Figs. 1 and 2, I have shown the garment upon a model, illustrating generally the appearance thereof upon an average sized model.

The garment comprises generally the lower body portion 10 and the upper body portion 12. The lower body portion 10 may be of the usual bloomer type comprising the leg portions 14 and 16 formed with the usual constricted leg openings 18 and 20. These openings may be formed with the usual binder 22 within which an elastic is placed in the usual manner familiarly known in the art.

The upper portion 12 may comprise the back portion 24 and the two front portions 26 and 28. As will be evident from the drawings, the front portions 26 and 28 are similar in all respects, the front portion 28, however, being attached at the seam line 30 to the bloomer portion 10, and the front portion 26 being attached only at the shoulder 32 and along one side to the waist line at the left side, 34.

The lower end of the front portion 28, as clearly shown in Fig. 4, may have a strap portion 36 extending therefrom through a suitable opening 38 formed at the side in the back portion 24 of the garment. The front portion 26 may likewise have a strap portion 40 attached to its lower end for a purpose which will be hereinafter apparent.

The lower edges 42 and 45 of the front pieces 26 and 28 are arcuately shaped, as shown on the drawings, so that when the garment is in place upon a wearer, the edge 42 of the portion 26 will be at a point below the waist line and will give a neat, trim appearance to the garment in position.

Referring to Fig. 3, the dotted line 44 illustrates the position taken by the edge 46 of the portion 26 when the garment is in place upon a wearer. The upper portion 12 may be provided with

sleeves or the same may be omitted, providing the arm openings 48 and 50.

When it is desired to attire in the garment which I have described, the garment may be taken in the position shown in Fig. 3 and by stepping through the opening caused by the forcing to one side of the movable front piece 26, the garment may be easily entered; and after the arms have been placed through the armholes 48 and 50, the front piece 26 is placed across the front of the person so that the edge 46 thereof is on the dotted line 44 and the edge 42 is along the lower edge 45 of the front piece 24. In this position the straps 36 and 40 are tied together in the rear of the garment, forming the knot 60. The garment is now in place upon the wearer and due to the possibility of the movement of front piece 26 for slight adjustment, the wearer can engage in strenuous exercises without displacing the garment or any of its parts in the manner which the garments of the prior art have been displaced.

The fact that the garment is secured in place by tying at the waist allows a garment of a standard size to be utilized by persons of various weights. For example, I have found by actual experiment that a size 16 garment may be worn by normal persons between the weights of 115 and 135 pounds. I have found that the appearance of the garment upon the maximum and minimum weight persons above described is equally attractive. This is due in a measure to the fact that the front portions are adjustable, as described, to accommodate various sized persons. Thus, female persons having an abnormal bust size, either large or small, may utilize the same size garment and have a trim fitting bodice due to the possible adjustment in fastening the garment on the person.

It should be further apparent from the description herein given that the utility of the garment is not limited to one in which bloomers are employed as the lower body portion. I contemplate that this construction can be embodied in garments having a lower trunk portion or a skirt portion with equal effect.

It is believed to be obvious that the appearance of the gym suit is greatly enhanced by the elimination of buttons or similar fastening devices at the shoulders or down the sides. The elimination of fastening buttons of any sort at any place upon the garment adds greatly to the life of garments of this type, especially in schools and gymnasiums where large numbers of garments are regularly worn. It is believed to be obvious that the garment which I have provided is much more comfortable than the garments of the prior art which employ a belt at the waist and a fastening at the shoulder or at the side. Due to the fact that the possibility of the breaking of buttons or

other fasteners is eliminated, it is easily understood that the garments will outlast such garments of the prior art in either normal or abnormal use.

While I have illustrated and described a specific embodiment of the invention, I do not wish to be limited to the exact details shown; rather what I desire to secure and protect by Letters Patents of the United States is:

1. An athletic garment for girls comprising a 10 bloomer portion and a bodice portion joined together at the waist line, said bodice portion having a right and a left shoulder embracing portion, said left shoulder portion extending from the left shoulder diagonally across the front of 15 the garment and fastening at the extended end and along its lower edge to the top of the bloomer portion, the right shoulder embracing portion being similarly shaped and extending diagonally across the front of the garment to the opposite 20 side, said right shoulder embracing portion having an arcuate lower edge and being adapted to fold over the outside of the left shoulder embracing portion, a strap attached to the extended end of said right shoulder embracing portion and a 25 strap attached to the extended end of the left shoulder embracing portion, said last mentioned strap adapted to pass through an opening near the top of the bloomer portion on the opposite 30 side of the garment from said first mentioned strap so that the garment may be adjustably fastened on a wearer by tying said straps together.

2. An athletic garment for girls comprising a 35 bloomer portion and a bodice portion joined together at the waist line, said bodice portion having a left and a right shoulder embracing portion, said left shoulder embracing portion extending from the left shoulder diagonally across the front of the garment and fastening at the extended end and along its lower edge to the top of the 40 bloomer portion, the right shoulder embracing portion being similarly shaped and extending diagonally across the front of the garment to the opposite side, said right shoulder embracing portion having an arcuate lower edge and being 45 adapted to fold over the outside of the left shoulder embracing portion, a strap attached to the extended end thereof and a strap attached to the extended end of the left shoulder embracing portion, said right shoulder embracing portion having a vertical slot adjacent the bloomer top, said last mentioned strap adapted to pass through said slot near the top of the bloomer portion on the opposite side of the garment from said first mentioned strap so that the garment may be adjustably fastened on a wearer by tying said straps together at the back of the garment.

ALEX E. SWANSON.
